COSMETIC HOLDER

Emil H. Orenick, Cleveland, Ohio

Application October 26, 1948, Serial No. 56,502

5 Claims. (Cl. 206—56)

1

This invention relates to cosmetic holders and particularly to swivel-type lipstick containers which expose the stick for use and withdraws the same into the casing after use.

The primary object of this invention is to provide a lipstick container which automatically opens or closes the opening through which the stick is exposed or withdrawn.

Another object is to provide a container of the type stated which retains a full length stick of cosmetic.

A further object is to construct such container so that the respective movements of the closure and the lipstick are synchronized so that when a maximum quantity of or a new lipstick is used it will not jam at the ejection opening with the cover.

Still another object of the invention is to design and construct a cosmetic holder of the type stated which may be easily made in large quantities by relatively simple standard tools and dies at an economical cost.

These and other objects of the invention will become apparent from a reading of the following specification and claims, together with the accompanying drawing in which like parts are referred to and indicated by like reference characters and wherein:

Figure 1 is a side view of the cosmetic holder with parts thereof broken away to show construction and assembly;

Figure 2 is a rear view thereof;

Figure 3 is a rear view of a top portion of the device;

Figure 4 is a view of the device with the case member thereof removed;

Figure 5 is another view of the elements shown in the Figure 4;

Figure 6 is a view of the device with the case and shell members thereof removed;

Figure 7 is another view of the elements and parts shown in the Figure 6;

Figure 8 is a horizontal sectional view of the device taken substantially along the line and in the direction of the arrows 8—8 of the Figures 1 and 3;

Figure 9 is a plane view of the cover element of the device;

Figure 10 is a view of the cover element of the device taken substantially along the line and in the direction of the arrows 10—10 of the Figure 9;

Figure 11 is a side view of the cover element of the device;

Figure 12 is a view of the lipstick and cup 75 thereof;

2

Figure 13 is another view of the elements shown in the Figure 12;

Figure 14 is another side view of the device in closed condition and showing the assembly of parts thereof;

Figure 15 is a view of the cosmetic holder in its open condition;

Figure 16 is an evolved view of the sleeve member of the device; and

Figure 17 is an evolved view of the shell member of the device.

The accompanying drawing shows a case member, a shell member, a sleeve member, a cup and a cover. Each of these members or parts are broadly indicated by the characters 20, 30, 40, 50 and 60 respectively.

The case member 20 is a metal or plastic hollow container substantially cylindrical in shape with a longitudinally extending flattened cover housing 70 that extends into the case top to form a hood 21 containing parallel tracks 24 as is shown in the Figures 2 and 8. The case member 20 has an opening 22 in the bottom thereof. The top of the case member at the hood 21 has a second or top opening 23 between the top ends of the tracks 24. The case member may be suitably ornamented as desired.

The shell member 30 has a top tubular portion 31 and a lower grip portion 38. The shell member alone is clearly shown in the Figures 6 and 7 and a flat or developed view thereof is shown in the Figure 17. The tubular portion 31 has a small retaining bead 32 around the top thereof which lies slightly below the opening 23 in the case member. The tubular portion 31 is formed with a longitudinal slot 33, sometimes referred to herein as the first slot. This longitudinal slot extends in a substantially straight line from the grip portion 38 to the bead 32. It may be slightly inclined as shown to facilitate the movement therein of the pin 51 of the hereinafter described cup 50. The inner edges of the tubular portion forming the slot 33 are referred to herein as the first or longitudinal cam element and are indicated by the character 34.

The tubular portion 31 also has a second or irregular slot 35 therein. This slot extends almost all the way around the tubular portion, and the ends thereof terminate on the sides of the first or longitudinal slot 33. A substantial portion 37 of the irregular slot 35 is circumferential as is clearly shown in the Figure 17. The inner edges of the second or irregular slot 35 are referred to as the second or irregular cam elements and are indicated by the reference character 36.

3

The grip portion 38 of the shell member is of a slightly greater diameter than the adjacent tubular portion 31 and joins the latter at a small shoulder 39. This grip portion may be suitably knurled or serrated to facilitate the operation of this novel container.

The sleeve member 40 is a cylinder-like piece of material which fits around the tubular portion 31 of the aforescribed shell member and is retained in place by the bead 32 and the shoulder 39. In practice it may be easily stamped out of flexible sheet metal and wrapped around the shell member as shown in the Figures 4 and 5. A flattened or developed sleeve is shown in the Figure 16. The sleeve member 40 nearly fits the shell member 30 as shown and is able to turn or rotate thereon without binding.

This sleeve member is stamped or formed with a third or spiraliform slot 43 and a fourth or lengthwise slot 45. The spiraliform slot 43 extends almost all the way around the sleeve and its bottom end is proximate to the bottom end of the longitudinal slot 33 and its top end is proximate to the top of the longitudinal slot 33. The bottom end of the spiraliform slot 43 has a slightly offset or lateral portion 47 as is clearly shown in the Figure 16. The inner side edge of the slot 43 and the lateral portion 47 thereof is referred to and indicated as the third or spiraliform cam element 44.

The fourth or lengthwise slot 45 is relatively short and lies substantially between the top and bottom ends of the spiraliform slot 43. As with the other slots, the inner side edge of this one is referred to and indicated as the fourth or lengthwise cam element 46.

The cup 50 is made of metal, plastic or other suitable material and is designed to hold the bottom end of the lipstick pencil 52 as is clearly shown in the Figures 12 and 13. The cup has a small pin 51 projecting outwardly from the side wall. The pin is long enough to pass through and be engaged simultaneously by the longitudinal and spiraliform slots 33 and 43 and is movable therein by the superimposed and co-acting cam elements 34 and 44.

The cover 60 is made of a thin flexible metal or plastic sheet and is slidably mounted in the longitudinally extending flattened housing 10. It has two parallel side edges 61 which fit the heretofore described grooves or tracks 24 in the case member hood. It has a concave edge 63 in its forward portion 62 which lies between the parallel side edges 61. Its lower or rearward portion 64 is tapered and has a small lug 65 extending therefrom which is designed to be engaged by the second or irregular slot 35 and the fourth or lengthwise slot 45 simultaneously. It is caused to move in these two slots by the co-action of the superimposed cam elements 36 and 46. The cover is clearly illustrated in the Figures 8, 9, 10 and 11.

The aforescribed members and parts are assembled as follows. First the cup 50 is inserted in the tube 31 of the shell with the pin 51 projecting through the longitudinal slot 33. The sleeve 40 is wrapped around the tube 31 and positioned so that the pin 51 projects through the slot 33 and also extends into the spiraliform slot 43. When so assembled the cup 50 will move upward in the assembled members when the shell member 30 is turned to the right or clock-wise in the sleeve member 40, and will move downward when the shell member is rotated in the opposite direction.

Next, the cover 60 is placed on the sleeve 75

4

member 40 so that the lug 65 projects inward and through both the fourth or lengthwise slot 45 and the second or irregular slot 35.

When assembled in this manner the cover 60 will move downward when the shell 30 is turned to the right or clock-wise in the sleeve 40 and will move upward when the shell is rotated in the opposite direction. It should be noted at this point that when the shell is rotated in the sleeve the cup 50 will move in one direction for the length of the longitudinal slot 33 while at the same time the cover 60 will move in the opposite direction for the length of the lengthwise slot 45.

The then assembled members 30 and 40 and the cup and cover 50 and 60 respectively are inserted into the case 20 with the concave edge 63 facing upward and with the parallel side edges 61 fitting the parallel grooves or tracks 24 in the hood 21. The case 20 is then lowered completely over the tube 31 and so that the edges of the bottom opening 22 fits sharply around the shoulder 39 of the grip. The assembly and fit of the case 20 over the sleeve 40 should be tight so that once assembled the case and sleeve act as a single unit and so that they are not too easily separated. The lower edge of the case should allow the shell 30 to freely turn when the grip thereof is rotated. When finally assembled, the lipstick 52 is inserted into the cup 50. Normally, or when the shell is turned to the left as far as it will go, the cup and lipstick are down and fully into the case and at the same time the cover 60 closes the opening 23.

One of the principal features or advantages that this device has over other similar devices is that it can contain a full length cosmetic pencil. Other similar automatically operating lipstick holders can not do this. For a better understanding of this particular feature, attention is directed to United States Patent 2,064,557 which shows a means for automatically and simultaneously opening a holder cover and raising the lipstick therein. There it will be observed that the lipstick pencil must be very much shorter than the length of the available space in the container. This shortening of the lipstick is therefore necessary to prevent the top of the lipstick from reaching the opening before the cover is fully opened.

In the instant device the movements of the cup 50 and the cover 60 are timed or synchronized so that the cover is fully opened before the lipstick cup 50 starts to move. This is caused by the slight inaction of the superimposed cams 34 and 44 on the pin 51 while the pin is in the lateral portion 47 of the spiraliform slot 43. Before the pin 51 reaches the spiral or upper cam portion of the slot 43, the top parts of the slots 35 and 45 have already acted on the lug 65 to move it downward.

The relative or required movement of the cover 60 is about half that of the cup 50 and for that reason the irregular slot 35 has a rather large circumferential portion 37 which does not act on the lug 65. When the lug 65 reaches the bottom of the lengthwise slot 45 and the circumferential portion 37 it will stop moving even though the lipstick continues to be projected through the opening. Similarly when the operation is reversed and the lipstick is withdrawn, the lipstick will move inward a substantial distance before the cover 60 starts to move upward to close the opening.

Another advantage that this holder has over

prior art devices, in addition to its greater capacity and efficiency, is that it may be operated easily with one hand and there are no separable covers to remove and to possibly lose. Its lipstick element may be easily replaced or renewed when the cup 50 is raised to its highest point as when the shell 30 is turned to the right as far as it will go.

The number of parts needed to form this cosmetic container are relatively few and each of them may be easily stamped or formed out of easily obtained materials and by processes well known to those skilled in the art.

It will now be clear that there is provided a device which accomplishes the objectives heretofore set forth. While the invention has been disclosed in a preferred and a modified form; it is to be understood that the specific embodiments thereof as described and illustrated herein are not to be considered in a limited sense as there may be other forms or modifications of the invention which should also be construed to come within the scope of the appended claims.

What is claimed is:

1. A cosmetic holder, comprising in combination, a case member including a hood portion at the top thereof and having a first opening on the bottom thereof, the said hood portion having parallel tracks therein and a second opening between the said tracks, a sleeve member inside of the case member and attached thereto, the sleeve member having a spiraliform slot and a lengthwise slot therein, a shell member including a tubular portion inside of the sleeve member and rotatable therein and including a grip portion extending through and rotatable at the said first opening, the shell member having a longitudinal slot and an irregular slot therein, a cup adaptable for retaining the said cosmetic movably mounted inside the shell member and having a pin thereon slidably engageable with the said spiraliform and longitudinal slots, and a unitary flexible cover for the aforesaid second opening movable on the said tracks and having a lug thereon slidably engageable with the said lengthwise and irregular slots, the members and the associated slots and the respective pin and lug therein being formed and positioned in a manner whereby rotation of the said grip portion in one direction with respect to the case member will cause the said cover to move away from the second opening and cause the said cosmetic to project therethrough and whereby rotation of the grip portion in the opposite direction will cause the cosmetic to return through the said opening and cause the cover thereof to close.

2. A cosmetic holder, comprising in combination, a case member including a hood portion at the top thereof and having a first opening on the bottom thereof, the said hood portion having parallel tracks therein and a second opening between the said tracks, a shell member including a tubular portion inside the case member and a grip portion in the aforesaid first opening, the said tubular portion having first and second cam elements thereon, a sleeve member mounted between the case and shell members and having third and fourth cam elements thereon, a cup adaptable for retaining the said cosmetic movably mounted inside the shell member and having a pin thereon movable by the first and third cam elements, and a unitary flexible cover for the aforesaid second opening movable on the said tracks and having a lug thereon movable by the said second and fourth cam elements, the members and the associated cam elements and the re-

spective pin and lug therein being formed and positioned in a manner whereby rotation of the said grip portion in one direction with respect to the case member will cause the said cover to move away from the second opening and cause the said cosmetic to project therethrough and whereby rotation of the grip portion in the opposite direction will cause the cosmetic to return through the said opening and cause the cover thereof to close.

3. A cosmetic holder, comprising in combination, a case member including a hood portion at the top thereof and having a first opening in the bottom thereof, the said hood portion having parallel tracks therein and a second opening between the said tracks, a sleeve member inside the case member and attached thereto, the said sleeve member having a spiraliform cam thereon and a lengthwise cam thereon, the said spiraliform cam having a lateral portion, a shell member including a tubular portion inside of the sleeve member and rotatable therein and including a grip portion extending through the said first opening, the said tubular portion having a longitudinal cam and an irregular cam thereon, the irregular cam having a circumferential portion, a cup adaptable for retaining the said cosmetic movably mounted inside of the shell member and having a pin thereon movably engageable with the aforesaid spiraliform and longitudinal cams, and a unitary flexible cover for the aforesaid second opening movably mounted between the case and sleeve members and having a lug thereon movably engageable with the aforesaid lengthwise and irregular cams, the members, pin and lug and their respective cams being formed and positioned in a manner whereby rotation of the grip portion in one direction will cause the cover to first move downward and thereafter cause the cup to move upward and whereby rotation of the grip portion in the opposite direction will cause the cup to first move downward and thereafter cause the cover to move upward.

4. A cosmetic holder, comprising in combination, a substantially cylindrical case member having a first opening in the bottom end thereof and including a longitudinally extending flattened cover housing having re-entrant side edges defining parallel track elements extending across the top of the said case member and forming a hood having parallel tracks therein and a second opening between the said tracks, a sleeve member inside the said case member and attached thereto, the said sleeve member having a spiraliform cam thereon and a lengthwise cam thereon, the said spiraliform cam having a lateral portion, a shell member including a tubular portion inside of the sleeve member and rotatable therein and including a grip portion extending through the said first opening, the said tubular portion having a longitudinal cam and an irregular cam thereon, the irregular cam having a circumferential portion, a cup adaptable for retaining the said cosmetic movably mounted inside of the shell member and having a pin thereon slidably engageable with the aforesaid spiraliform and longitudinal cams, and an unitary flexible cover for the aforesaid second opening slidably mounted in the said housing between the said track elements and having a lug thereon slidably engageable with the aforesaid lengthwise and irregular cams, the members, pin and lug and their respective cams being formed and positioned in a manner whereby rotation of the grip portion in one direction will cause the uni-

tary flexible cover to first move downward in its housing and thereafter cause the cup to move upward and whereby rotation of the grip portion in the opposite direction will cause the cup to first move inward and thereafter cause the cover to move upward in its housing.

5. A holder for lipsticks and the like comprising an outer tubular casing member which is circular in cross section throughout the major portion of its periphery and which has one side projecting and flattened and which curves away from the flattened side at one end, said one end having a central opening therein, means including an inturned flange forming a track at opposite sides of said opening, an inner tubular casing member fitting fixedly in the outer casing member with its side wall spaced from the flattened side of the casing, a unitary flexible closure fitting between the flattened wall of the outer casing member and the inner tubular cas- 20

ing member and fitting in said tracks, means in one of the casing members defining an axially extending cam track, a sleeve rotatable in the outer casing member projecting from the other end thereof and formed with an operating knob by which it can be turned, a spiral cam track on the sleeve, and projecting means on the closure engaging the cam tracks whereby the closure will be shifted axially in the casing when the sleeve is turned.
